Norman Stein, Outremont, near Montreal,
Quebec, Canada

Application May 23, 1946, Serial No. 130,024
In Canada December 29, 1945

Term of patent 7 years

(Cl. D15—1)

To all whom it may concern:

Be it known that I, Norman Stein, a subject of the King of Great Britain, residing at 770 Champagneur Avenue, in the city of Outremont (near Montreal), Providence of Quebec, Dominion of Canada, have invented a new, original, and ornamental Design for Combined Seat and Telephone Stand, of which the following is a specification, reference being had to the accompanying drawing, forming part thereof.

Figure 1 is a front perspective view of the combined seat and stand, and

Figure 2 is a similar view at a different angle, showing the telephone shelf.

I claim:

The ornamental design for a combined seat and telephone stand, as shown.

NORMAN STEIN.
